PRINTING MECHANISM

James W. Bryce, Bloomfield, N. J., assignor, by
mesne assignments, to International Business
Machines Corporation, New York, N. Y., a cor-
poration of New York

Application August 28, 1930. Serial No. 478,339

15 Claims. (Cl. 101—96)

This invention relates to printing tabulators and more particularly to printing tabulators which are adapted to print the alphabet.

In tabulating machines, speed of printing is a desideratum and previous machines have been devised in which a rotating drum is employed carrying the type carriers and in which the type carriers were individually called into action to strike and imprint characters upon paper carried by a platen during the rotation of the drum. A construction of this sort is particularly adaptable for speed of operation because there is no necessity for an idle resetting movement of the parts due to the continuous forward rotation of the drum which carries the type carriers.

A construction of this general type is shown and described in Carroll Patent No. 1,516,079. The construction of the aforesaid patent was adapted for printing numerical items. In printing numerical characters only 10 type are required for printing the various digits but for printing alphabetical characters a much greater number are required, viz. 26 for the alphabet and if both alphabet and numerals are to be printed, 35 or 36 type are necessary. Accordingly, it has been heretofore proposed to provide a multiplicity of type on the drum and to print either the alphabet or numerals from such type. A construction for this purpose is shown in Carroll Patent No. 1,623,163, dated April 5, 1927. While a fair speed of operation can be secured, the drum is comparatively large in size and is somewhat objectionable for this reason. It has also been proposed heretofore to use on a drum construction combined alphabetical and numerical type, each type bar having for example, three type characters thereon and to selectively print not only from the different type carriers on the drum, but to also selectively print from the different type of each bar.

Heretofore when this manner of printing was employed, for example according to Carroll Patent No. 1,726,539, dated September 23, 1929, it was proposed to shift the platen to a different elevational position for each of three successive revolutions of the drum. On each revolution a different type character was printed. This construction while providing for greater compactness of the drum construction hampered the speed of printing reducing it one-third over that attainable for the numerical lister.

According to the present invention, provision is made for retaining the compactness of the simple numerical lister and for also retaining its speed of printing while at the same time pro-

viding for the printing of the desired alphabetical characters.

It is accordingly one object of the present invention to provide a construction which is capable of effecting a selection and the obtaining of printed impressions from multiple character type on type bars while the latter are in motion and during one revolution of the drum which carries such type bars.

It is a further object of the present invention to provide a construction wherein shiftable elements carrying multiple type are provided upon the type bars and wherein means are provided for shifting the type relatively to the carrying bar while the carrying bars are in flight and in motion.

Further and other objects of the present invention will be hereinafter set forth in the accompanying specification and claims and shown in the drawings which by way of illustration show what I now consider to be a preferred embodiment of the invention.

In the drawings:

Figure 1 is a side elevational view shown partly in section showing a printing drum having type arranged for numerical and alphabetical printing and provided with the selecting devices which are required for selecting the type for printing action. This view also shows the related adding mechanism;

Fig. 2 is a somewhat enlarged view of a fragment of the drum drawn on a greater scale and showing certain of the parts which are shown in Fig. 1 with certain parts in moved position;

Fig. 3 is a view somewhat similar to Fig. 2 but showing the parts in a still further displaced position in which a particular selection is being effected;

Fig. 4 is a diagrammatic view showing the controlling perforations which are employed on the record card and the corresponding numerical and alphabetical characters which they represent;

Fig. 5 is an elevational view of one of the translators including a relay which are used for controlling selecting action;

Fig. 6 is a perspective view of the translator shown in Fig. 5;

Fig. 7 is a developed diagrammatic view of the translator and associated commutator portion elements and includes the electrical circuit diagram of the translator;

Fig. 8 is a wiring diagram of the complete machine and this view shows somewhat diagram-

matically some of the mechanical parts used in the machine;

Fig. 9 is a detail view of certain restoring devices which are in the translator shown in Fig. 5; 5 Fig. 10 is a sectional view taken on line 10—10 of Fig. 9;

Fig. 11 is a view similar to Fig. 1 but with a modified form of type element and selecting construction; and

10 Fig. 12 is a view showing certain parts shown in Fig. 11 and in a movable or displaced position.

Referring to Fig. 1, 20 is the printing drum provided with the type restoring cam shafts 21 and with any suitable driving train for rotating the 15 drum, for example the driving train 22 shown by the dotted line gears. Disposed in the drum are the rows of type carriers 23. The type carriers co-act with the camming shafts 21 in the manner fully described in Carroll Patents Nos. 1,516,079 20 and 1,726,539 and accordingly this description will not be repeated here.

Magnets 24 are the primary selecting magnets and it is the energization of these magnets under record card control that makes the primary selection 25 and calling of the type carriers into action. It is sufficient to here state that the energization of magnets 24 trip latches 25 which in turn are positively actuated by the heels 26 of succeeding type to in turn actuate hook 27 and displace such 30 hook 27 into position for calling a type by swinging action into position. This mechanism is substantially identical with the mechanism of Carroll Patent No. 1,726,539. In Figs. 1 and 2, 28 is the platen carrying the usual sheet of paper 29.

35 In contradistinction to the construction heretofore provided in machines of this class, each type carrier is provided with a multiplicity of type, i.e. 30, 31, 32 (Fig. 2), and such type are mounted so as to be relatively movable with respect to their supporting carrier 23. Fig. 3 shows one construction in which the type carrying element 33 is relatively slidable on the carrier 23.

It will be noted that the aggregate number of 45 type on the carriers is greater than the number of the carriers themselves. For example, in the embodiment shown, there are three times as many type as there are carriers for the type.

Secondary selection of type

50 According to the present invention, provision is made for effecting a primary selection of the type carriers by energization of magnets 24 in the manner heretofore explained and in addition there is a secondary selection of the type for printing. This secondary selection is made while the type carriers are swinging towards printing position and while the carriers are in continuous forward motion. The particulars of the secondary selecting devices will now be described.

60 Referring to Fig. 3, disposed in alignment with the path of movement of the end of the type elements 33 is a camming element 34 preferably pivoted upon a shaft 35 and having a camming face 36 disposed to contact with the curved end of element 33.

Referring to Fig. 1, synchronously with the rotational movement of the drum 20, a cam device 37 displaces a cam follower 38 and through a linkage 39 swings down a bail 40 (see also Fig. 3). The elements 34 are connected to the bail by suitable springs 41 and the same elements are provided with stepped ratchet or stopping teeth designated 42 and 43. During operation of the machine there is an energization of a secondary selecting magnet 44 which magnet according to

its time of energization trips a latch 45 and trips a pawl 46 causing it to engage one of the steps 42, 43 or to miss the 43 step entirely. The particular step which is engaged will depend upon the time of energization of magnet 44. It will accordingly be seen that the part 34 and camming face 36 have three possible positions. One of these positions will be that in which 34 rests in contact with bail 40 in which case 46 will have missed the notch 43. The next position is that shown in Fig. 3 in which 46 has been engaged with notch 43 and the last position will be that in which 46 has engaged notch 42. It is according to which of these positions that part 34 with its camming face 36 assumes that will control the extent of outward displacement of member 33. Member 33 moves outwardly under the influence of centrifugal force during the swinging movement of the carrier 23.

Accordingly by the above secondary selecting mechanism provision is made for selecting which of the type 30, 31 or 32 will impact against the platen and this selecting action is effected during one revolution of the printing drum so that any one of the greater number of type can be caused 100 to print during such single revolution of the drum. There is accordingly a concurrent selection of type carriers and type for printing action. While the piloting part 34 receives a preliminary set up the actual selecting action occurs while 105 the type carrier 23 is swinging outwardly under the influence of the primary selecting mechanism.

The means for controlling the secondary selection will now be described.

Referring now to Fig. 8, 50 designates a stack 110 of record cards which are adapted to be handled and advanced in the usual way in succession one by one, by suitable feed rolls such as 51. Suitable card sensing means are provided comprising brushes and contact blocks 52, 53. A next 115 lower set of brushes and contact blocks 54, 55 and in addition a still lower set of brushes and contact blocks 56, 57 is provided. Contact blocks 55 connect to plugboard sockets generally designated 58 and from these sockets connection can 120 be optionally made to leads 59 leading to counter magnet 60 or to leads 61 which lead to rotary switching devices 62 and from thence to the primary selector magnet 24 and back to the other side of line. Other leads 63 also extend to the 125 switching devices generally designated 62 and at their opposite end connect to the brush blocks 57 as shown. The details of the switching devices 62 will be subsequently explained after the translators have been described.

Assuming a record card being fed into the machine, one of the record cards is traversed past the upper brushes and brush blocks 52 and 53. The position of these brushes and brush blocks is such that they are adapted to read the upper 135 three pilot holes on the record card which are marked "Control" on Fig. 4 of the drawings. According to which holes are encountered in these control holes timed circuits are established through a circuit which for one column will be 140 traced as follows: from block 53 through 79, Fig. 8, to brush 71, (see also Fig. 7) thence to common conducting ring 72 on commutator elements 73 and thence selectively at the 10, 11 and 12 positions to one of the three brushes 74 and via 145 one of the circuits 75 to one of the three magnets 76, 77 or 78. Energization of one of the magnets 76 or 77 or 78 allows its cooperating brush (Fig. 7) 76a, 77a, or 78a to shift with relation to their cooperating commutators generally design- 150

nated 79 and 80. This effects the translator brush set up. The circuit passes from either of the magnets 76, 77 or 78 back to a local circuit 81 to the other side of line.

5 The structure which is employed for effecting the shifting of brushes is shown in further detail in Fig. 6 and is the same as is usually used for this purpose in translating devices.

10 As the commutators 79 and 80 rotate during the operation of the machine and during the rotation of the drum 20 and depending upon the relative shifting or non-shifting of brushes 76a, 77a and 78a, a timed differential circuit will be established to the secondary selecting magnet 44 15 at either of three differential times which in time correspond to the three desired positions of elements 34. In this way the secondary selection control is obtained.

20 As shown in Fig. 4, the one to nine index point positions representative of numerals are adapted to be read by the lower brushes 54. When alphabetical characters are to be read there are multiple holes in the index point columns and it will be noted that there are certain holes marked 25 "Extra holes". These extra holes require an additional set of brushes for reading and such reading is effected by brushes 56. Further to the right on the record card, Fig. 4, in the beginning of zone 2, there are again certain alphabetical 30 characters which are read conjointly by the lower brushes 54 and by the upper brushes 52. It is accordingly necessary to provide switching mechanism to selectively determine whether the record is to be read by brushes 54 for the lower 35 brush positions or whether brushes 56 are to be used for reading the extra hole positions.

Translating mechanism

40 The operation of the translating mechanism in translating from multiple or single hole readings as shown in the control columns of Fig. 4 may be understood from the development diagram of Fig. 7. The reading-in commutator 73 rotates in the direction indicated by the arrow, 45 carrying its conducting spots into cooperation with brushes 74. The spacing of the spots is such that the spot in 10 position makes contact with its brushes 74 at the time when analyzing brush 52 of the machine is searching the 10 index point 50 position on a card; the spot in 11 position makes contact with its brush when the analyzing brush is searching the 11 index point position and so on.

55 The circuits established energize the various magnets 76, 77 and 78 to shift their respective brushes 76a, 77a, and 78a as heretofore explained. For example, if B is represented on the card as indicated in Fig. 4, the magnet 76 will be energized through the zero perforation of this character.

60 When the magnets 76, 77, 78 are deenergized their brushes are in positions indicated on the drawings while if any magnet is energized its corresponding brush is shifted to an alternative position.

65 The brushes 76a, 77a, 78a ride on the surface of reading-out commutators 79, 80 which are provided with a blank insulating surface which is opposite the brushes during that portion of the cycle in which the shiftable brushes are being set up under control of reading-in commutator 73. After they have been completely set up they coact with conducting spots 90 on the reading-out commutator surface. Two circumferential 70 rows of spots 90 are provided for each brush, the brush coacting with one row in its normal un-

shifted position and cooperating with the other row when it is shifted by its magnet. These spots are also arranged in transverse rows on the commutators, which as indicated by the horizontal row of digits below the commutator 80 correspond in pairs to the machine positions in which impulses through the secondary selector magnets 44 will result in positioning the camming element 34. These pairs of transverse rows are passing beneath the brushes 76a, 77a, 78a synchronously with the passage of the notches 42, 43 of Fig. 3 past latch 46 so that if, for example, an impulse occurs when either of the "16" rows of spots is under the brushes, latch 46 will be tripped to coat with notch 43 as shown in Fig. 3.

80 With the particular arrangement of the spots 90, if any character contains control perforations in accordance with Fig. 4 the appropriate brushes will be shifted in combinations to cause a current impulse through the secondary selector magnet 44 at the proper time to set camming element 34.

85 The operation will be clearer from a specific example. Assume that a card feeding past the brush 52 bears perforations in its 5, 11, and 12 index point positions representing the character W. When the brush 52 encounters the index perforation in the 11 index point position the 11 spot of the reading-in commutator 73 is under a brush 74 and a circuit is instantaneously established through magnet 77 thus shifting the brush 77a from contact with the upper row of the lower rows of spots 90 into cooperation with the adjacent row. When the brush 52 encounters the 95 perforation in the 12 index point position, the brush 78a will be similarly shifted. By tracing the circuits in Fig. 7 it will be noted that with 100 brushes 77a and 78a shifted a circuit is completed when and only when the left row of conducting spots 90 of zone 3 is under the brushes; brushes 77a and 78a being bridged at this time by the connected spots on the commutator 80. This results in an impulse through magnet 44 as 105 follows: Referring also to Fig. 8 current will flow from the right side of line to wire 91, brush 78a, connected spots 90 in the left column of zone 3, brush 77a, wire 92, brush 76a, spot 90 which is connected to ring 93, brush 94, wire 95 to magnet 44 and thence back to line. This energization 110 of magnet 44 takes place previous to the arrival of the leading edge of the card at the lower 115 brushes 54 which now sense the index point positions 9 to 1 to energize the primary selecting magnet 24 to print the character represented. 120

125 Continuing the tracing of the circuits involved in the example under consideration, when the 5 hole arrives at brush 54 the circuit will follow from brush 54, block 55, wire 61 to a brush 96, riding on a common ring 97, to insert 98, a brush 99 normally traversing the insert 98, wire 100, magnet 24, back to line. Insert 93 is so proportioned that brush 99 is traversed thereby only during the card interval from 9 to 1 so that 130 brushes 54 are ineffective to complete a circuit through any of the control holes.

135 The selection of a character for printing under control of brushes 54 has been described. Other characters represented by perforations in accordance with the "Lower brush" fields of zones 1, 2 and 3 of Fig. 4 will result in selecting the corresponding type elements in a similar manner.

Switching device

140 Where the character being analyzed is one of 150

- those in the "Extra" field, the switching commutator 62 will function to cause this column to be read by the brushes 56 after the zone has been selected. Assuming the specific character to be 5 the letter F, the circuit will be (Fig. 7) on a line 91, brush 78a, connected spots 90 in the right column of zone 2, brush 77a, wire 92, brush 76a, spot 90 in the right column of zone 2, which is connected to a ring 101, brush 102, wire 103, switching magnet 104, wire 105, to magnet 44. In the same manner for each character represented in Fig. 4 under the field headed "Extra" the selecting circuit for magnet 44 will be serially through switching magnet 104.
- 10 Magnet 104 is adapted to shift brush 99 in a manner identical with the shifting of brushes 76a etc., so that the brush moves out of the path of insert 98 and into that of an insert 106 so that as the card continues through the machine a circuit will be established through the 2 index point hole of the selected letter P from brush 56 to block 57, wire 63, brush 107, ring 108, insert 106, brush 99, wire 100 to magnet 24. This energizes magnet 24 at the time the carrier 23 bearing letter P arrives in printing position. Brushes 54 and 56 are so related that brush 56 cooperates with the 4 index point position of the card immediately after the 1 index point has passed the brush 54 so that the carriers 23 successively present the characters to printing position in the order outlined in Fig. 7 above commutator 72.
- 15 The general mechanical structure of the switching mechanism is similar to that of the translators and commutators 62 and 79 have been formed integral for convenience and mounted on a common gear 109 (Figs. 5 and 6) which is driven in synchronism at a ratio of one to one with the printing drum 20 (Fig. 1) through the gearing shown.
- 20 Any of the brushes 76a, 77a, 78a which are displaced from normal latched position are automatically restored after the brushes have traversed spots 90 and prior to subsequent energization of any of their magnets under control 25 of the reading-in commutator.
- 25 The restoring mechanism (Figs. 5, 9 and 10) consists of a pivoted arm 110 whose free end underlies the ends of brushes 77a and 78a and which has pin and slot connection with a lever 30 111 whose opposite end underlies brush 76a. Arm 110 carries a pin 112 which at the proper time in each cycle is engaged by a cam 113 (Fig. 5) on the driving gear of commutator 80 to rock arms 110 and 111 to restore the brushes which 35 remain in normal latched position as in Fig. 6 until their magnets are again energized to release the latching mechanism.
- 40 Brush 99 is similarly restored through an arm 114 having a pin 115 cooperating with a cam 116 on gear 109 which returns brush 99 to normal position after all of the carriers 23 have presented themselves to printing position.
- 45 Where it is desired to add from certain columns on the card, such columns will be connected from their plugs 53 (Fig. 8) to the plugs terminating wires 59. It will be noted in connection with Fig. 4 that the perforations representing digits involve no control holes and that the holes are arranged in the well known Hollerith manner 50 so that no effective circuits will be established through brushes 52 or 56 and items will be accumulated from the card in the regular manner.
- 55 The adding mechanism which is shown diagrammatically in Fig. 1, at 120, may be similar

to that shown and described in Carroll Patent No. 1,726,539. It will be appreciated that with the present improved construction of printing mechanism and with the improved selection of type by primary and secondary selecting action, which primary and secondary selection is made during one revolution of the printing drum, that it is possible to effect adding during one revolution of the drum and that in the same single revolution of the drum it is possible to select or print all of the letters of the alphabet and the numerals.

60 Accordingly, a record controlled machine can print alphabetical characters and concurrently add at the speed heretofore only obtainable for adding and printing numerical characters alone. In other words, notwithstanding that provision is made for alphabetical printing, the printing of the alphabet does not hamper the speed of the adding.

65 Accordingly, the present construction provides a tabulating machine in which one speed of operation of the printing elements can be used for both listing, adding and listing, adding alone, or adding with accompanying alphabetical printing. Heretofore when alphabetical printing was attempted the speed of machine operation as a whole was hampered or the drum proportions were so increased that adding took place in one portion of the cycle followed by subsequent alphabetical printing. Heretofore, accordingly it has not been possible to have concurrent adding with alphabetical printing and with unhampered speed of operation.

70 The adding mechanism consists briefly of a plurality of index wheels 125 which are driven through gear trains from counter shafts 126 geared to cross shaft 127. Shaft 127 is constantly rotating and one gear of each train carries clutch teeth 128. A coacting clutch member 129 is splined to shaft 126 to rotate with it, but may be shifted under control of magnet 60 into clutching position thereby rotating the gear train and the registering element 125 with the shaft 126. At a predetermined point in each machine cycle any 75 clutches which are in engaged position are automatically unclutched and restored to the position of Fig. 1 thereby arresting the motion of registering elements 125 in their new positions. It will thus be obvious that the registering 80 position of the elements 125 is determined by the differential time during the machine cycle when an operating pulse is supplied to magnet 60 by brush 54. This accounting mechanism is fully described in the Carroll Patent 105 No. 1,726,539 to which reference may be had for a complete explanation.

85 A modification of the printing mechanism is illustrated in Figs. 11 and 12. In this form the parts corresponding to those in the other figures are represented by the same reference characters with the latter *a* added. The drum 20a has a greater number of carriers 23a and each carrier has pivoted upon its free end a printing element 33a having type 150, 151. A 90 spring detent 152, cooperates with suitable notches in 33a to hold the member in position to print upon the platen 28a from either of the type.

95 The secondary selecting magnet 44a is adapted to position a camming element 153 in the path of arms 154 of elements 33a where it is held by a latch 155. The normal position of cam 153 is out of cooperation with arms 154. A restoring bail 156 is adapted when rocked to actuate latch 150 155 thus releasing cam 153. With the cam in

the position of Fig. 11 each arm 154, in succession, will be engaged and its element 33a rocked from the relative position of Fig. 12 where type 150 is in active position to move type 151 into effective position so that as the carriers 23a move into printing position the selection of one of them by primary magnet 24a will cause printing from type 151. Cams 157 on cam shafts 21a serve to rock elements 33a back to normal position after they have passed platen 28a.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope 20 of the following claims:

1. In a record controlled machine, means for sensing cards in motion, a rotary drum adapted to advance a group of type to and past a printing position during the passage of a single index position past the sensing means and a cyclically operable selecting device controlled by said sensing means for controlling the selection of one of the type in said group.

2. In a printing machine having a rotatable drum carrying type carriers each having multiple type thereon, a plurality of sensing stations, means for feeding cards through said stations, one of said stations being responsive to a perforation in separate predetermined positions on a card, selecting mechanism controlled thereby, type positioning means controlled by said selecting mechanism for selecting a type on each carrier and means controlled through another of said sensing stations, responsive to a perforation in the card for actuating one of said carriers to cause the selected type thereon to print.

3. In a card controlled printing machine having card sensing means, a rotatable drum carrying groups of type carriers, each carrier having multiple type thereon and type selecting mechanism comprising primary, secondary and tertiary, group, carrier and type selecting means, and means controlled by said card sensing means for making a primary selection of a group of type carriers, a secondary selection of a carrier in a selected group and a tertiary selection of a type upon the selected carrier, said selections being effective during a single rotation of said drum.

4. In a printing machine having a rotatable drum carrying groups of type carriers, each carrier having multiple type thereon and type selecting mechanism comprising primary, secondary and tertiary group carrier and type selecting means and means operative in one rotative cycle of the drum for making a primary selection of a group of type carriers, a secondary selection of a carrier in the selected group and a tertiary selection of a type upon the selected carrier.

5. In a card controlled printing machine having card sensing means, groups of type carriers, each carrier having multiple type thereon and type selecting mechanism comprising primary, secondary and tertiary group carrier and type selecting means, and means controlled by said sensing means for making a primary selection of a group of type carriers, a secondary selection of a carrier in a selected group and a

tertiary selection of a type upon the selected carrier.

6. A card controlled printing mechanism comprising card sensing means, a plurality of groups of continuously movable type carriers, each with a plurality of type thereon which are relatively movable with respect to the type carrier, and means controlled by said sensing means for concurrently selecting a group of carriers, a particular carrier within said group and a particular type upon a carrier for printing action.

7. A printing mechanism for a record controlled machine in which a type carrying drum is provided carrying a plurality of groups of type carriers, each type carrier with a plurality of type thereon and in which a sensing means is provided and including in combination means for sensing one record for each revolution of the printing drum, means for effecting a concurrent major, intermediate and minor selection of the type during one revolution of the drum.

8. In a machine of the class described, means for analyzing a perforated record card comprising primary, secondary and tertiary sensing means, a plurality of groups of type carriers, each carrier with multiple type thereon, means controlled by said primary sensing means for selecting a group of carriers for printing action, means controlled by said secondary and tertiary sensing means for controlling which of the carriers of a group is to be actuated and further means controlled by said primary sensing means for controlling the operation of said secondary and tertiary sensing means.

9. In a record controlled machine for operating upon combinational index point records and translating the readings thereon into single timed current impulses, comprising a rotatable drum carrying type carriers each having multiple type thereon, record analyzing means, translating mechanism settable under control of said analyzing means, selecting mechanism settable under control of said translating mechanism to select a type upon each carrier for printing said translating mechanism being adapted to cooperate with said analyzing means to convert the readings into single timed current impulses.

10. In a record controlled machine having a rotatable drum carrying type carriers each having multiple type thereon, sensing means adapted to sense perforations in combinational index point records, a rotatable commutator and brushes shiftable relatively thereto under control of said sensing means in accordance with combinations of index points on the records to convert the readings into single timed current impulses, and selecting means controlled by said commutator to select one of said type for operation.

11. In a record controlled machine, means for feeding record cards having index points, a rotatable drum having type carriers thereon each carrier carrying multiple type, sensing means cooperating with certain predetermined index points of a card in motion, a plurality of magnets selectively operated under control of said sensing means, brushes shiftable under control of said magnets, commutators cooperating with said brushes, circuits adapted to be selected by said brushes and commutators for controlling the time of operation of said selected circuit and selecting mechanism controlled by said circuit for selecting a type for operation.

12. In a record controlled printing machine, a plurality of type elements, record controlled

electrically actuated selecting means adapted to select several non-adjacent elements of said plurality of type elements and electrically actuated means controlled by a record and by said selecting means for presenting one of said selected elements to printing position.

13. In a record card controlled machine, means for continuously feeding cards through the machine, means for advancing a group of type in succession to and past the printing position during the passage of a single index point position of a card with respect to a fixed point in the machine, and means controllable by a perforation in the card for selecting one of said group of type for operation during the passage of said index point position.

14. In a machine of the class described having feeding means adapted to feed record cards successively, sensing means adapted to sense the cards index point by index point, a type carrier,

and a plurality of type carried thereby, cooperating with a platen, means for moving said carrier synchronously with the movement of the card so that several type move through printing position during the movement of a single index point past said sensing means, and means controlled by said sensing means for selecting one of said several type for operation.

15. In a machine of the class described, having feeding means adapted to feed perforated record cards, card sensing means adapted to sense a perforation in a card in motion, a type carrier, a plurality of type carried thereby, means for moving said type to printing position during the cooperation of said sensing means with a perforation, and means controlled by said sensing means for selecting one of said type for printing.
